UNITED STATES PATENT OFFICE.

GEORGE S. BOSWORTH, OF TROY, NEW YORK.

BOILER-FURNACE.

SPECIFICATION forming part of Letters Patent No. 228,976, dated June 22, 1880.

Application filed November 14, 1879.

To all whom it may concern:

Be it known that I, GEORGE S. BOSWORTH, of Troy, county of Rensselaer and State of New York, have invented certain new and useful Improvements in Boiler-Furnaces, of which the following is a full, clear, and exact description, reference being had to the accompanying drawings, and to the letters of reference marked thereon.

10 Figure 1 is a front elevation of a stationary boiler, showing the tubular grate-bars in cross-section, the register-damper being omitted the better to show the location and arrangement of said bars. Fig. 2 is a central longitudinal section of the same boiler, showing the combustion-chamber and grate, the partition, damper, back fire-plate, grate-bearings, and bottom of hot-air chamber being in cross-section; and Fig. 3 is a plan of same, showing the 15 grate in position, the diagonal shading representing the brick-work or boiler-setting. Fig. 4 is a central longitudinal section of a locomotive-boiler, showing my improvements applied thereto. Fig. 5 is a longitudinal section 20 of a portion of a marine boiler, showing my improvements applied thereto, as in the previous figures, the boiler being provided with two fire-grates, and indicating the application of my invention to such boilers as now made.

30 Like letters of reference in all the figures indicate corresponding parts.

The object of my improvements is to effect a more complete combustion of fuel used in boiler-furnaces than is possible in any of the 35 ordinary arrangements, and thereby lessen the amount of fuel required and increase the amount of steam produced.

The invention has relation to all manner of boilers used for the generation of steam; and 40 it consists in certain new and useful combinations or arrangements of parts, whereby the air to support combustion is first thoroughly heated by the burning gases and the fuel upon the grate, and then conducted downwardly 45 through the mass of fuel between the grate-bars and out with the inflamed gases, provision being made for tempering the fire by reversing the draft through the fuel, or by passing a current of air over it, (one or both;) and 50 the construction involves, in connection with the other essential and well-known elements

of the furnace, the use of fire-grates made of tubes or pipes (either wrought or cast metal) arranged and secured in proper position, having both ends open—one for the admission of air either from an artificial blast or natural draft, and the other for the discharge of air into the air-chamber for the purpose of heating the same before it comes in contact with the fuel, (thereby making a hot-air furnace;) a 55 partition set across the furnace and joining the boiler-shell, crown-sheet, or water-space, (as the construction of the boiler may make necessary in stationary, locomotive, and marine boilers,) having proper and sufficient openings, 60 with damper or dampers to regulate the amount of draft or blast required; a back fire plate or wall fitted and set over the tubular grates at or near their inner ends at a proper distance from the before-mentioned partition, and extending upward a sufficient distance to secure 65 the proper depth of fire-box, and forming an air-chamber, into which the heated air is discharged after passing through the tubular grates; a sufficiently extensive combustion-chamber under the tubular grates and between 70 the partition flue-sheet and water-space in locomotive and marine boilers, and between said partition and bridge-wall in stationary boilers, 75 into which the gases are conducted in a downward direction and inflamed and passed through the entire length of the flues under and through said boiler, preventing the escape of unconsumed gases; and a damper so located and arranged in the above-mentioned 80 partition that when it is turned down it will close the openings between the bridge-wall and the back fire-plate, causing the air from the tubular grates to pass down into the combustion-chamber, then upward through the 85 fuel and over the damper through the openings in the partition, thence to the flues, for the purpose of controlling the fire as necessity may require, which parts or elements are combined and arranged as hereinafter explained, 90 or as in the claims specially set forth.

A A are the tubular grates, B B the combustion-chamber, and C the back fire-plate or fire-wall. The tubes A A are supported at front and rear, as at h' and h, the front ends 95 being left open for the inflow of air, governed, if desired, by a damper, as at a, Figs. 2 and 3,

and the discharge ends opening into the hot-air chamber *b*. This hot-air chamber *b* communicates with the space above the fuel, and when the damper *d* is turned up, as indicated by the full lines in all the figures, the course of the feed-air is as follows: Entering at the open ends of the tubes, it is highly heated therein, and passes directly to the hot-air chamber *b*, where it is further heated, and from this chamber it passes upward and over the fire-plate or fire-wall *C*, then downward through the ignited fuel and between the tubular grates *A* into the combustion-chamber *B B*. When the boiler is arranged as in Fig. 2, the ignited 15 gases are conveyed onward through flue *f* to the back of boiler, then through the return-flues to the smoke-stack, as indicated by the arrows. In Figs. 4 and 5 the arrangement is shown to be such that the ignited gases enter 20 the boiler-flues immediately upon leaving the combustion-chamber.

The damper *d* is hung in the partition *e*, which separates the hot-air chamber *b* from the combustion-chamber, and so arranged that 25 when turned up it will close the communication between said chambers, except through the mass of fuel upon the grates, and when turned down, as indicated by the dotted lines, will cause the feed-air to pass from chamber *b* 30 into chamber *B B*, and thence upward through the fuel and out through partition *e* over the top of the damper, thus reversing the direction of the current or draft.

The inner bearing, *h*, for the grates is fitted 35 and fastened to the partition *e*, and it also forms the bottom of the hot-air chamber. The outer or front bearing, *h'*, is secured to the front of the boiler. The partition *e* is fitted into suitable fastenings at the sides and top 40 of the furnace (allowance for expansion in all cases being made) in stationary boilers, and to the water-legs or water-spaces forming the sides of the furnace in locomotive and marine boilers. The back fire-plate or fire-wall, *C*, is 45 fitted over the grates and secured to the sides of the furnace in the same manner as the partition.

To start the fire I put the fuel on the grates and the kindlings on the top of the fuel. The 50 air or draft is admitted through the tubular grates into the air-chamber, then upward and over the back fire plate or wall into the firebox, thence downwardly through the ignited fuel and the spaces between the tubular grates 55 into the combustion-chamber, thence to the boiler-flues, filling said chamber and flues with flame instead of unconsumed gases or smoke. Thus complete combustion results, and I am 60 enabled to increase the temperature of the boiler, so as to evaporate more water with less fuel than can be done under any other form or arrangement of which I am aware.

From the foregoing description it will be observed that the arrangement is quite simple,

and the practical results of its use indicate 65 its thorough efficiency for the purposes intended. By the arrangement shown I am enabled to obtain the desired downward flow of air through the fuel when the maximum effects are required. I can reverse the draft through 70 the fuel at pleasure in order to temper or dampen down the fire, or by opening the feed-door and turning the damper down I can quickly extinguish the fire by permitting a draft of cold air over its top. The fire may 75 also be controlled by regulating the quantity of feed-air admitted by use of the damper *a*.

Since the feed-air is intensely heated while passing through the tubular grates and the hot-air chamber before coming in contact with 80 the fuel, I collect and use a great amount of heat that would otherwise be lost, and by the introduction of the highly-heated air into the burning fuel the gases are liberated therefrom in a better condition to unite with the oxygen 85 contained in the feed-air.

The combustion-chamber *B B* should be of ample size to allow for the expansion of the inflamed mixture of air and gases; otherwise 90 the proper complete combustion could not result.

The damper *d* is provided with a handle, *g*, Fig. 3.

In the double furnace indicated in Fig. 5 the arrangement for both fires is the same as in 95 the single furnace, and either fire may be controlled in accordance with the foregoing explanations.

In Fig. 4 the draft-inlet extends beneath the combustion-chamber. This construction is 100 mainly intended for use in connection with locomotive-boilers, and possesses many advantageous features in such connection.

Having thus fully described my invention, what I claim as new, and desire to secure by 105 Letters Patent, is—

1. The combination of the tubular grates *A*, hot-air chamber, partition *e* and damper mounted therein, and the combustion-chamber, the arrangement being substantially as 110 described, so that the direction of the draft may be changed from downward to upward through the fuel by simply turning the damper, substantially as shown and explained.

2. In a boiler-furnace, the combination of 115 the tubular grate-bars, hot-air chamber, firebox, enlarged combustion-chamber communicating with the boiler-flues, and the partition *e*, with dampered aperture, the whole being combined and arranged substantially as shown 120 and described.

In testimony that I claim the foregoing I have hereunto set my hand in the presence of two witnesses.

GEORGE S. BOSWORTH.
